UNITED STATES PATENT OFFICE.

WILLIAM C. HEDGCOCK, OF CHICAGO, ILLINOIS, ASSIGNOR TO AMERICAN STEEL
FOUNDRIES, OF NEW YORK, N. Y., A CORPORATION OF NEW JERSEY.

BRAKE-BEAM.

1,185,314.

Specification of Letters Patent. Patented May 30, 1916.

Application filed March 2, 1916. Serial No. 81,597.

To all whom it may concern:

Be it known that I, WILLIAM C. HEDGCOCK, a citizen of the United States, residing at Chicago, in the county of Cook and State 5 of Illinois, have invented certain new and useful Improvements in Brake-Beams, of which the following is a specification.

My invention relates to railway brakes, and has particular reference to a novel 10 brake beam.

In the use of certain types of brake arrangements it is common to provide brake riggings which are duplicated on each side of the truck, whereby the pull is applied at 15 a point close to the brake heads, the heads being connected by a beam or bar.

An object in the present invention is to provide a beam adapted for the use referred to, which shall combine the elements of simplicity and adaptability to the desired location, and which shall, in addition, provide means in connection therewith for supporting the beam and the rigging.

The beam is illustrated in its association 25 with a car truck in my co-pending application, Serial No. 81,598, filed March 2, 1916.

The invention will be more readily understood by reference to the accompanying drawings, wherein—

30 Figure 1 is a plan view of a brake beam constructed in accordance with my invention; Fig. 2 is an edge elevation of the same, and Fig. 3 is an end elevation thereof.

Referring more particularly to the drawings, it will be seen that the beam in its preferred embodiment is of generally I-beam shape in cross section and comprises a web 10, and the flanges 11. The beam terminates 35 at its ends in trunnions 12, which are shown as designed to accommodate an angularly adjustable brake head 13. A pair of apertured lugs, or ears, 14, 15, are provided at each end of the beam at a point close to the brake head, the pulling levers, or force 40 applying means, being connected to the beam at this point. At a point substantially midway between the lugs 14, 15, I provide a similar pair of apertured lugs 16, which provide for the connection thereto of a sup-

porting link, or lever, fulcrumed on a rigid 50 portion of the car truck. All the parts heretofore described, except the brake head, are formed in an integral casting in the preferred construction. It will be readily apparent, however, that the essence of my invention does not reside in the integral casting 55 but in the conception of a simple beam of this type which shall provide for the connection of the pulling levers at points close to the brake heads, and for a supporting means at a point near the longitudinal center line of the truck; that is, at a point midway of the length of the beam. Obviously also the head may not be adjustable, and other modifications may be made in the 60 construction shown, all without departure 65 from the spirit of my invention.

I claim:

1. A brake beam, comprising a bar providing mountings at its ends for brake 70 heads, and three sets of attaching lugs projecting laterally from said beam, the sets of lugs near the end of the beam providing for the connection of brake levers, the intermediate lugs providing for the attachment 75 of a supporting device, substantially as described.

2. A brake beam, comprising a bar, the ends of which are adapted to be secured in 80 brake heads, a brake lever pulling lug located near each end of and projecting laterally from said bar, and a supporting lug located at substantially the middle of the bar, substantially as described.

3. In a brake beam, the combination of 85 a bar providing trunnions at its end, brake heads mounted on said trunnions, brake lever attaching lugs located at each end of said beam and a supporting lug located intermediate the end of the beam, substantially as described.

Signed at Chicago, Illinois, this 28th day of February, A. D. 1916.

WILLIAM C. HEDGCOCK.
